BALL THROWING DEVICE

Myron Fleishman, 3471 Fenton Ave., New York, N.Y.

Filed Oct. 27, 1960, Ser. No. 62,638

Term of patent 7 years

(Cl. D34—15)

FIG. 1

FIG. 2

FIG. 1 is a top plan view of a ball throwing device showing my new design;

FIG. 2 is a side elevation view;

FIG. 3 is a perspective view.

The broken line showing of balls in FIGS. 1 and 2 are for illustrative purposes only.

I claim:

The ornamental design for a ball throwing device, as shown and described.
